LINEN CART

David P. Beary, 1634 W. Farwell Ave., Chicago, Ill.

Filed Sept. 11, 1964, Ser. No. 81,689

Term of patent 7 years

(Cl. D14—3)

FIG. 1 is a top plan view of a linen cart showing my new design;

FIG. 2 is an elevational view of one side thereof;

FIG. 3 is an elevational view of the rear thereof;

FIG. 4 is an elevational view of the other side thereof; and

FIG. 5 is an elevational view of the front thereof.

I claim:

The ornamental design for a linen cart, substantially as shown.
